HEAT TRANSFER SYSTEM AND METHOD

Application filed July 17, 1930. Serial No. 468,601.

My present invention is shown as embodied in systems primarily devised for transfer of heat from a region or space to be maintained at a desired refrigerant temperature to a refrigerant source, and includes means whereby a very intense, that is to say, low temperature refrigerant may be used for refrigeration at a much higher temperature, the preferred refrigerant being solidified carbon dioxide in various forms, compounds and mixtures, notably approximately pure carbon dioxide, at approximately 110° below zero F. However, various features of the invention are applicable to various lower temperature refrigerant sources as, for instance, liquid air, or higher temperature refrigerant sources such as a brine tank, maintained at any temperature sufficiently below the temperatures being maintained in the refrigerated space. As my invention contemplates transfer of the heat by boiling of a liquid in the refrigerated region and recondensing the resulting vapor to liquid by the refrigerant source, the latter must be one adapted to maintain the condenser portion of the system at a temperature substantially below the boiling point of the heat transfer medium.

The heat transfer medium will be selected as preferred. In general, a higher boiling point medium may be employed where the desired refrigerating temperature is relatively high or the heat leaks to be refrigerated against are relatively small, but its freezing point should be below the temperature of the condenser. The specific medium selected may be any of those known to the art, for instance, sulphur dioxide (SO_2), ammonia (NH_3), carbon dioxide (CO_2), methyl chloride (CH_3Cl), propane (C_3H_8), etc.

The systems shown herein include control of temperature of the refrigerated space by having the heat absorbing coil or evaporator part of the circuit flooded, not flooded, or partly flooded, either (a) by locating said evaporator in gravity flow relation to the condenser and employing a thermostatically operated valve between the coil and the condenser to control, permit or prevent flow of the condenser liquid from said condenser into said evaporating coil; or (b) to effect the

same control of gravity flow by moving the vapor coil above or below the level of the liquid in the condenser; or (c) by locating the coil at or above the level of the condenser and providing a lift line in the form of a small capacity boiler exposed to the heat of the refrigerated space in such relation that part of the liquid in said lift coil will be evaporated, the incipient bubbling thus produced serving to decrease the specific gravity of the liquid in the lift line so that it is unbalanced and forced upward by the cold liquid in the condenser and, when the boiling becomes pronounced, the bubbles of vapor will exercise a pronounced air lift effect so that when proportioned and designed to suit the conditions, the main evaporator will be properly charged or flooded with liquid. This will occur when temperatures in the refrigerated space are too high. Consequently, such liquid flooded into the evaporator will rapidly absorb heat from the refrigerated space, and the resultant boiling of the liquid will maintain the evaporator at constant or controlled temperature according to the internal pressure on the system.

In order to effect further control, said pressure within the system may be predetermined and automatically adjusted by means of a pressure valve in the line between the evaporator and the condenser whereby when the internal pressure becomes too low by reason of fall of temperature in the refrigerated space, the return flow of vapor to the condenser will be blocked.

My invention also includes a specific improved arrangement of condenser with reference to solid carbon dioxide as the refrigerant, whereby the rate of heat transfer to the condenser is reduced so that other things being equal the temperature of the condenser itself may be substantially higher than that of the solid carbon dioxide refrigerant. This may be of advantage with any of the above mentioned heat transfer liquids since operativeness of my apparatus depends mainly on the heat absorbed by the boiling in the evaporator; and the cooling of the liquid far below the boiling point, after it has been condensed, is unnecessary.

The above and other features of my invention may be more fully understood from the following description in connection with the accompanying drawings, in which

- 5 Fig. 1 is a somewhat diagrammatic vertical section of a container enclosing a refrigerated space, equipped with a heat transfer system embodying one form of my invention;
- 10 Figs. 2 to 7 are similar sections showing a similar, more diagrammatic form, various modifications;

Fig. 8 is a detail view of condenser contained in Fig. 1.

- 15 In Fig. 1 the refrigerated space 1 is shown as enclosed by heat insulating casing which may comprise exterior and interior gas-tight shells 2 with intervening heat insulating material 3 enclosing, preferably at a high level 20 therein, a refrigerant container 4 which may be charged with refrigerant such as solid carbon dioxide 5 by removing the hatch 6.

The insulation 4 may be very heavy so that only a negligible amount of heat can 25 be absorbed through the walls thereof, directly from the refrigerated space, but it is only necessary that this insulation be sufficient so that the refrigerant effect thus directly exerted upon the refrigerated space 1 30 will be at all times insufficient to keep the temperature of the refrigerating space 1 down to the desired maximum. That is to say, so long as such direct refrigeration is insufficient, the control of the exact desired 35 temperature will reside in my heat transfer system which I will now describe.

The heat transfer circuit comprises a condenser 7, from the bottom of which the condensed liquid flows through pipe 8 into the 40 refrigerated space, thence upward through an accelerating heat absorbing coil 9 and through pipe 10 into the top of a boiler 11. The liquid gravitates to the bottom of this boiler and the vapor therefrom escapes 45 through pipe 12, control valve 13 and pipe 14 back to the condenser 7. While the liquid may be any known or desired liquid such as those above mentioned, we may assume for present purposes that sulphur dioxide (SO_2) 50 is used. The amount of liquid charged into the system should be such that even when the amount of liquid contained in the condenser 7 and coil 9 is a maximum, there will still be some liquid left in the bottom of the 55 evaporator 11.

The liquid in evaporator 11 is exposed to the atmosphere in the refrigerated space 1 and, absorbing heat from the latter, will 60 evaporate sufficiently to generate a pressure in the system corresponding to the saturation pressure of sulphur dioxide for that temperature. The vapor in the condenser 7 will of course be at the same pressure as in 11, but being in contact with the cold surfaces 65 of the condenser 7 will condense, thereby

tending to drop the pressure in the system. This drop in pressure will lower the temperature at which the sulphur dioxide vaporizes in the evaporator. For a definite size of evaporator 11 and condenser 7, the system will be in a dynamic state of equilibrium with a pressure and corresponding evaporator temperature somewhat below the temperature of the refrigerated space 1. In other words, the coil will be sufficiently below the temperature of said space so that the sulphur dioxide will boil at the same rate that the condenser 7 can condense it. The boiling off of the liquid removes some of the heat from the evaporator 11 and lowers the temperature in the refrigerated space 1. The coil and condenser will now come to equilibrium for this lower temperature in space 1; the temperature of the evaporator will drop and correspondingly the pressure in the entire system will drop.

It is thus evident that the functioning of the system is governed in accordance with its internal pressure and an important feature of the particular system shown in this Fig. 1 is providing the valve 13 between the evaporator 11 and condenser 7, which may be used to control this pressure, preferably automatically. When the valve is open, the above described cycle of boiling in the evaporator 11 and condensing in the condenser 7 continues unmodified, but if the valve be closed, the vapor escaping from the evaporator cannot flow through its normal path to the condenser and the pressure automatically rises, the result being that the boiling point of the liquid in the system is raised above the temperature of evaporator 11. Of course, the rise of pressure takes effect as a back pressure through coil 9, but this has no other effect than to force part of the liquid in that coil back into the condenser. Boiling being thus prevented, the rate of heat absorption in coil 11 is greatly decreased, thereby permitting the temperature in space 1 to rise. While such a valve could be operated by hand or thermostatically, the present preferred arrangement is one in which the valve automatically opens upon rise of pressure, thereby permitting vapor again to flow into the condenser and closes on fall of pressure cutting off such flow. The means diagrammatically indicated for this purpose is a metallic bellows 15, the exterior of which is exposed to atmospheric pressure through vent 16, and the interior of which is exposed to the interior pressure of the system through inlet 17. The normal position of the valve is controlled by balance between an interior spring 18 and exterior spring 19 and may be set to operate at desired internal pressures by an adjusting screw 20, whereby the exterior spring 19 may be put under greater or less initial pressure tending to close the valve 13. It will be noted that the inlet to the evap-

orator 11 is at a point above the normal level of liquid in the system and no liquid would normally flow by gravity from the condenser into said evaporator except for the operation of coil 9. This coil is a heat absorber of limited capacity shown as warmed by the atmosphere in the refrigerated space 1, but it may be arranged in the walls of the refrigerator or partly or wholly outside the same. 5 The heat operates first to decrease the specific gravity of the liquid in this coil, up to the boiling point thereof; and thereafter will cause incipient bubbling and ultimately boiling of the liquid in said coil to whatever extent may be necessary to decrease the specific gravity of the liquid to a point where the cold, heavy liquid remaining in the condenser will overbalance the light liquid in 9 and force some of the mixture to flow into the 10 evaporator 11.

It will be noted that in thus functioning, the lift coil 9 is thermostatic in so much as the warmer it gets, the more effective it will be in lifting liquid and supplying it to the 15 evaporator.

A special feature of the system shown in Fig. 1 is the peculiar form of condenser and means for conducting heat therefrom into intimate and sure heat exchange relation 20 with the solid carbon dioxide. In the form shown in Fig. 1, and more in detail in Fig. 8, the condenser consists of two plates, 27, 28, held parallel by spacer framing strip 29 affording a condenser interspace 30 which is 25 rendered gas-proof under any pressure that may be exerted in the system by welding the plates to the spacer. As shown in Fig. 8, the spacer is preferably formed with an inclined bottom so that all liquid may be 30 drained therefrom through pipe 8. The rear plate, 28, of the condenser is integral with a horizontal plate 28a extending laterally over the bottom of the bunker, so that the solid carbon dioxide 5 rests on said plate. 35 With such an arrangement, the heat from the condenser reaches the solid carbon dioxide mainly by conduction through the all metal path afforded by 28a, and the amount of heat absorbed depends on the area of contact of the refrigerant block 5 with said plate. 40 Consequently, said block 5 may be evaporated down to a thin slab before there is any substantial decrease in the refrigerating effect which it exerts on the condenser. The 45 heat conveyed from the condenser to the refrigerant may be still further limited to that which flows through the all metal path by applying a layer 31 of compressed cork or other heat insulating material over the face of 50 condenser plate 30, between it and the refrigerant 5.

The carbon dioxide gas evolved in container 4 maintains the latter full of pure cold gas which has a remarkable insulating effect 55 and further limits leak of heat to the solid

carbon dioxide 5 except through the all metal path 28, 28a. The surplus gas overflows from the top of container 4 into an interspace 40 in which it circulates and from which it is preferably discharged at a high level, in this case 70 through exterior vent 41, although it may be permitted to spill into the refrigerated space if desired, or may be returned to the bunker.

Other modified systems in accordance with my present invention are illustrated in Figs. 75 2 to 7 inclusive. In these figures, parts corresponding to Fig. 1 are represented by the same reference numerals, distinction between figures being preserved by the use of different exponents for the numerals of each 80 figure.

In Fig. 2, the space 1a is to be cooled to, and maintained at, some definite temperature considerably higher than the temperature of the source of refrigeration which is contained in 4a and which may be very cold 85 brine, solid carbon dioxide, liquid air or the like. For a specific case, one may assume that the refrigerant is solid carbon dioxide which evaporates at a temperature of -110° 90 F. and that space 1a is to be cooled to a temperature of 40° F.

The condenser 7a is indicated as a coil in refrigerant compartment 4a so that if vapor of some volatile liquid is introduced there- 95 in, its latent heat will be removed, thereby condensing it to liquid. This condenser is connected by pipe 8a with the evaporator 11a which is in the refrigerated space 1a and is at a lower level so that liquid from the condenser 7a will drain by gravity into the top of 100 said evaporator and the lower end of the latter is connected by pipe 12a with the top of condenser 7a. Drainage of liquid is controlled from the condenser into the evaporator by a valve 13a, which is diagrammatically indicated as controlled by a thermostatic bulb. This may be one of the many known types adapted to open the valve 13a when 105 the temperature in space 1a tends to rise above the desired temperature and to close said valve when the temperature tends to drop below the desired temperature.

In operation we may assume that the condenser 7a is filled with sulphur dioxide; that bunker 11a 110 contains solid carbon dioxide; and that space 1a is at a temperature of 70° . Since the bulb F is adjusted to open valve 13a at 40° , liquid in 7a is free to flow into coil 11a. The warm atmosphere around 11a vaporizes 115 the liquid and the vapor flows through pipe 12a to the condenser 7a where its heat of vaporization is removed and it becomes liquid. This liquid drains into coil 11a, where it is again vaporized, thereby removing more heat 120 from space 1a. This cycle continues until the desired temperature (40° F.) is reached in space 1a, whereupon the thermostatic bulb closes valve 13a, so that liquid sulphur dioxide 125 can no longer flow from 7a to 11a and re- 130

frigerating of space 1a is arrested. As soon as the temperature starts to rise, the bulb again opens valve 13a and the cycle of the sulphur dioxide through the system is resumed and continues until the temperature is again lowered to the point where the bulb F will again close the valve 13a. Thus, as long as there is refrigerant in bunker 4a sufficient to condense the sulphur dioxide vapor, space 1a will be maintained at 40° F. although the temperature of the refrigerant is about -110° F. Similarly, the valve 13a can be adjusted for other temperatures such as 50° or 20° or 0°, but the cycle of operation would be the same as before.

It will be noted that in the system shown in Fig. 2, the regulation is not apt to be so close as that in Fig. 1, because the thermostatically controlled inlet valve 13a of Fig. 2 is between the condenser drainage pipe 8a and the top of the evaporating coil 11a. Consequently, any liquid left in 11a when the thermostatic valve 13a closes is free to boil and flow to condenser 7a, thus preventing any rise of pressure such as operates to discontinue the boiling in Fig. 1 where the valve is between the evaporator and the condenser.

The control valve is, and in all systems may be, the well known type of snap-action valve now employed in mechanical refrigerators the characteristic of which is that it remains wide open until a predetermined low pressure is reached and, having reached this low pressure and having closed, it remains closed until a predetermined high pressure is reached.

In Fig. 2, the evaporator 11a has to be at a low level in order to insure gravity drainage of liquid into it from the condenser 7a and this is frequently undesirable because the bottom of the refrigerator naturally tends to be the coldest part thereof and unless the heat is absorbed in the upper warmer part of the atmosphere, the convection currents will not be sufficient to maintain reasonable uniformity of temperature between the top and the bottom of said space. However, the system shown in Fig. 2 may be made to operate with the coil in the upper part of the refrigerated space by providing an air lift pipe 9b, which operates on the principle described in connection with the coil 9 of Fig. 1, that is to say, if the system is filled with liquid to the height indicated by the dotted line x, the part of it in 9b being exposed to the heat in the upper part of the refrigerated space 1b, will cause incipient boiling sufficient to lift liquid through the distance x plus y, whenever the thermostatic valve 13b is open. Obviously, said valve 13b can be located in the return conduit 12b if desired, in which case vapor formed in 11b after the valve is closed will be cut off from condenser 7b and can only take effect as back pressure raising the level of the liquid in the condenser 7b. Obviously, such a valve can be located anywhere in the

exterior part of the circuit in or between the condenser outlet 8b and the condenser inlet 12b.

The evaporator coil may be modified in several ways without changing the basic principle of operation. In Fig. 4, coil 11c is supposed to be the same as coil 11b of Fig. 3, but it is provided with short circuiting pipes 11w, 11x, to afford short paths for vapor return from different parts of the coil so that the vapor will not tend to lift the liquid back towards its source.

In Fig. 5, I have shown means whereby the liquid may be raised to an evaporator coil lid, located at any desired height. This is accomplished by one or any desired number of loops 11y, 11z, connected in parallel to the low level drainage pipe 8d of condenser 7d and re-entering the raiser pipe 9d at a substantially higher level. In this way a desired amount of the cold liquid may be heated enough to lift it to the required height. The heat and the absorbing capacity of these loops may be such as to cause practically all of the frosting to occur on said loops, leaving the evaporator coil 11d free from frost or alternately frosted and defrosted, in cases where the refrigerant temperature in 1d is at or above the freezing point of water.

If it is necessary or desirable to elevate the evaporator 11d, to a level as high or higher than that shown in Fig. 5, additional lifting effect for the liquid in 9a may be obtained by using as many loops, with as much heat absorbing surface as may be necessary to give proper "air lift" for the liquid, in any particular case. If a thermostatic valve is used, it can be placed either in evaporator coil 11d or in the loops themselves.

In Fig. 6, I have shown how two different compartments, 1x, 1y, can be refrigerated at different temperatures by separate evaporators 11e and 11f, connected in parallel with the same refrigerant condenser 7e. While any of the herein described systems can be thus connected to a single source, by the use of lifting loops or coils where these are necessary, the specific form here shown is where one of the evaporators is below the level of the condenser and in this case the condensed liquid in 8e passes through branch pipes 8f and 9f, each provided with an outwardly opening check valve 8g, 9g, while the vapor returns are connected with 12 by pipe 12f, 12a, respectively. 12g will contain a standard control valve 13, which may be of the type shown in Fig. 1, while 12f will be controlled by snap action control valve 13a such as described in connection with Fig. 2.

Thus, there are two heat absorbing systems operating independently from the same condenser 7e. When the compartment 1y reaches a desired temperature, say 10°, valve 13 will operate to discontinue evaporation in evaporator 11e. Likewise when 11f pro-

duces its desired temperature, say 40°, valve 13a will operate to discontinue the refrigerative effect.

The above noted tendency of the lift line 5 to respond thermostatically to the temperature in the refrigerated space may be utilized as the sole thermostatic control factor of the system, one arrangement for such purpose being indicated in Fig. 7 where the condenser 10 7n has a reservoir 7o to assist in determining a definite normal level for liquid in the condenser while the evaporator 11n is located wholly above said level so as normally to contain no liquid. In this case the drainage 15 pipe 8n drains directly into a loop 11o, which exposes enough heat absorbing area in the refrigerated space 1n so that the liquid is warmed above the frosting point by the time it reaches the lift coil 9n. Normally, the cold 20 liquid flows to the bottom leg of the coil 11o and as it becomes heated rises into the lift coil 9n, the shunt pipe 8o having little or no effect on this natural thermocirculation of the liquid. However, when bubbling and 25 upflow of liquid becomes copious, 8o may come into action to supply liquid directly to the lift coil, 9n. The coil 11o may have such heat absorbing capacity as to warm the liquid above the frost point, when the refriger- 30 ant temperature in 1n is substantially above 32° F., otherwise there may be frost on lift coil 9n, but the functioning will be upon the same principle as where there is no frost formation. That is to say, the main evapora- 35 tor 11n, being above the normal level of the liquid in the system will be normally dry and the only boiling that occurs will be in the loop 11o and lift coil 9n. Whenever this becomes excessive, however, the liquid will pro- 40 gressively invade the evaporator 11n and the heat absorption and transfer will be increased accordingly.

I claim:

1. A method of refrigeration which in- 45 cludes evaporating a liquid by heat absorbed in a region to be cooled; conducting resulting vapor in operative relation to the refrigerant, to recondense the same to liquid, said recon- densation taking place in one portion of a 50 condenser while the heat is conducted to the refrigerant in a different portion of the con- denser through a comparatively thick metal- 55 lic path; conducting the liquid back to the region to be cooled in continuous circuit; and controlling evaporation to control the tem- perature in the refrigerated region by con- 60 trolling flow of fluid between the evaporator and the condenser.

2. A method of refrigeration which in- 65 cludes evaporating a liquid by heat absorbed in a region to be cooled; conducting resulting vapor in operative relation to the refrigerant, to recondense the same to liquid, said recon- densation taking place in one portion of a 70 condenser while the heat is conducted to the

refrigerant in a different portion of the con- denser through a comparatively thick metal- 75 lic path; conducting the liquid back to the region to be cooled in continuous circuit; and controlling evaporation to control the tem- 80 perature in the refrigerated region by pre- venting return flow of the vapor to the con- denser.

3. A method of refrigeration which in- 75 cludes evaporating a liquid by heat absorbed in a region to be cooled; conducting resulting vapor in operative relation to the refrigerant, to recondense the same to liquid, said recon- densation taking place in one portion of a 80 condenser while the heat is conducted to the refrigerant in a different portion of the con- denser through a comparatively thick metal- 85 lic path; conducting the liquid back to the region to be cooled in continuous circuit; and controlling evaporation to control the tem- 90 perature in the refrigerated region by caus- ing decrease of pressure in the system to cut off return of the vapor to the condenser.

4. A method of refrigeration which in- 90 cludes evaporating a liquid by heat absorbed in a region to be cooled; conducting resulting vapor in operative relation to the refrigerant, to recondense the same to liquid, said recon- densation taking place in one portion of a 95 condenser while the heat is conducted to the refrigerant in a different portion of the con- denser through a comparatively thick metal- 100 lic path; conducting the liquid back to the region to be cooled in continuous circuit; and controlling evaporation to control the tem- 105 perature in the refrigerated region by utilizing changes of pressure in the system due to changes of temperature in the refrigerated space to control return flow of the vapor to the condenser.

5. A method of refrigeration which in- 110 cludes evaporating a liquid by heat absorbed in a region to be cooled; conducting resulting vapor in operative relation to the refrigerant, to recondense the same to liquid, said recon- densation taking place in one portion of a 115 condenser while the heat is conducted to the refrigerant in a different portion of the con- denser through a comparatively thick metal- 120 lic path; conducting the liquid back to the region to be cooled in continuous circuit; and controlling evaporation to control the tem- perature in the refrigerated region by utilizing changes of pressure in the system due to changes of temperature in the refrigerated 125 space to cut off flow of the vapor to the con- denser when the temperature falls below pre- determined minimum and to permit flow to the condenser when the temperature rises above a predetermined maximum.

6. A method of refrigeration which in- 130 cludes evaporating a liquid by heat absorbed in a region to be cooled; conducting result- ing vapor in operative relation to the re- frigerant, to recondense the same to liquid;

conducting the liquid back to the region to be cooled in continuous circuit; and controlling evaporation to control the temperature in the refrigerated region by locating the inlet to the evaporative portion of the circuit at a level higher than the normal level of condensed liquid in the circuit and utilizing heat absorbed from the refrigerated space by the liquid in its path from condenser to the evaporator to warm and partially vaporize the liquid to lift it above said normal level a distance sufficient to cause the liquid to overflow into the evaporator.

7. A method of refrigeration which includes evaporating a liquid by heat absorbed in a region to be cooled; conducting resulting vapor in operative relation to the refrigerant, to recondense the same to liquid; conducting the liquid back to the region to be cooled in continuous circuit; and controlling evaporation to control the temperature in the refrigerated region by locating the inlet to the evaporative portion of the circuit at a level higher than the normal level of condensed liquid in the circuit and utilizing heat absorbed from the refrigerated space by the liquid in its path from condenser to the evaporator to warm and partially vaporize the liquid to lift it above said normal level a distance sufficient to cause the liquid to overflow into the evaporator or to not overflow, according as the amount of heat so absorbed is greater or less.

8. The method of modifying the refrigerative effect of solid carbon dioxide on a condenser that has a condenser portion and a plate extending therefrom which includes conducting the heat from the condenser through an all-metal path including said metal plate and upon which the solid carbon dioxide is supported.

9. A closed circuit refrigerating system including an evaporator for boiling a liquid by heat absorbed in a region to be cooled; a conduit conducting resulting vapor to a condenser in operative relation to a refrigerant, thereby recondensing the same to liquid, said recondensation taking place in one portion of the condenser while the heating is conducted to the refrigerant in a different portion of the condenser through a comparatively thick metallic path; a return conduit for conducting the liquid back to the region to be cooled, in continuous circuit; and means for controlling the temperature which includes valve means for controlling, permitting or preventing flow of fluid in said circuit.

10. A closed circuit refrigerating system including an evaporator for boiling a liquid by heat absorbed in a region to be cooled; a conduit conducting resulting vapor to a condenser in operative relation to a refrigerant, thereby recondensing the same to liquid, said recondensation taking place in one portion of the condenser while the heating is con-

ducted to the refrigerant in a different portion of the condenser through a comparatively thick metallic path; a return conduit for conducting the liquid back to the region to be cooled, in continuous circuit; and means for controlling the temperature which includes valve means for preventing return flow of the vapor to the condenser.

11. A closed circuit refrigerating system including an evaporator for boiling a liquid by heat absorbed in a region to be cooled; a conduit conducting resulting vapor to a condenser in operative relation to a refrigerant, thereby recondensing the same to liquid, said recondensation taking place in one portion of the condenser while the heating is conducted to the refrigerant in a different portion of the condenser through a comparatively thick metallic path; a return conduit for conducting the liquid back to the region to be cooled, in continuous circuit; and means for controlling the temperature which includes automatic valve means utilizing decrease of pressure in the system to cut off return of the vapor to the condenser.

12. A closed circuit refrigerating system including an evaporator for boiling a liquid by heat absorbed in a region to be cooled; a conduit conducting resulting vapor to a condenser in operative relation to a refrigerant, thereby recondensing the same to liquid, said recondensation taking place in one portion of the condenser while the heating is conducted to the refrigerant in a different portion of the condenser through a comparatively thick metallic path; a return conduit for conducting the liquid back to the region to be cooled, in continuous circuit; and means for controlling the temperature which includes automatic valve means utilizing decrease of pressure in the system to cut off return of the vapor to the condenser.

13. A closed circuit refrigerating system including an evaporator for boiling a liquid by heat absorbed in a region to be cooled; a conduit conducting resulting vapor to a condenser in operative relation to a refrigerant, thereby recondensing the same to liquid, said recondensation taking place in one portion of the condenser while the heating is conducted to the refrigerant in a different portion of the condenser through a comparatively thick metallic path; a return conduit for conducting the liquid back to the region to be cooled, in continuous circuit; and means for controlling the temperature which includes automatic valve means operating to cut off flow of the vapor to the condenser when the temperature falls below predetermined minimum and to permit flow to the condenser when the temperature rises above a predetermined maximum.

14. A closed circuit refrigerating system

including an evaporator for boiling a liquid by heat absorbed in a region to be cooled; a conduit conducting resulting vapor to a condenser in operative relation to a refrigerant, thereby recondensing the same to liquid; a return conduit for conducting the liquid back to the region to be cooled, in continuous circuit, the inlet to the evaporator being at a level higher than the normal level of condensed liquid in the system and the liquid supply conduit to the evaporator being designed and located to absorb heat from the refrigerated space to warm and partially vaporize the liquid to lift it above said normal level a distance sufficient to cause the liquid to overflow into the evaporator.

15. A closed circuit refrigerating system including an evaporator for boiling a liquid by heat absorbed in a region to be cooled; a conduit conducting resulting vapor to a condenser in operative relation to a refrigerant, thereby recondensing the same to liquid; a return conduit for conducting the liquid back to the region to be cooled, in continuous circuit, the inlet to the evaporator being at a level higher than the normal level of condensed liquid in the system and the liquid supply conduit to the evaporator being designed and located to absorb heat from the refrigerated space to warm and partially vaporize the liquid to lift it above said normal level a distance sufficient to cause the liquid to overflow into the evaporator or not to overflow, according as the amount of heat so absorbed is greater or less.

16. Refrigerating apparatus, including a closed circuit through a condenser in heat transfer relation to a refrigerated source, a discharge conduit for liquid therefrom, an evaporator in the refrigerated space into whch said conduit discharges, a return conduit for vapor from the evaporator to the condenser, the inlet of the evaporator being at a level above the normal level of liquid in the condenser and the liquid discharge conduit from the condenser to the evaporator having in shunt thereon an auxiliary conduit exposed to heat from or varying with the temperature of refrigerated space and of heat absorbing capacity sufficient to cause partial boiling of liquid therein to lift the liquid in said discharge conduit above the level of the liquid in the condenser and discharge it into the evaporator.

17. Refrigerating apparatus, including a closed circuit through a condenser in heat transfer relation to a refrigerant source, a discharge conduit for liquid therefrom, an evaporator in the refrigerated space into which said conduit discharges, a return conduit for vapor from the evaporator to the condenser, designed and operating to maintain above freezing temperatures in the refrigerated space, the liquid discharge conduit from the condenser exposed to heat from the atmos-

phere of the space to be refrigerated and of heat absorbing capacity sufficient to warm the liquid above frost collecting temperature before it enters the evaporator.

18. Refrigerating apparatus, including a closed circuit through a condenser in heat transfer relation to a refrigerant source, a discharge conduit for liquid therefrom, an evaporator in the refrigerated space into which said conduit discharges, a return conduit for vapor from the evaporator to the condenser, said latter conduit having a low level loop exposed to the atmosphere of the space to be refrigerated and of heat absorbing capacity sufficient to substantially warm the liquid before it enters the evaporator.

19. Refrigerating apparatus, including an outer heat-insulating casing provided with an inner gas-tight shell forming an interspace for circulation of carbon dioxide gas between it and the outer casing; a container for solid carbon dioxide in the upper portion of said chamber, arranged for overflow of gas therefrom into said interspace and provided with heavy heat insulation between it and the chamber to be refrigerated, thereby minimizing direct heat transfer; a metal condenser therein having its inlet at a relatively high level and its outlet at a lower level and having a transverse integral extension upon which solidified carbon dioxide refrigerant is supported, thereby affording an all metal path for transfer of heat from the condenser to the refrigerant; a discharge conduit from the lower portion of the condenser extending into the refrigerated space, an evaporator in the refrigerated space into which said conduit discharges, a return conduit closing a closed circuit return for vapor from the evaporator to the condenser, and means for controlling the rate of evaporation in the evaporator by and in accordance with the temperature of the refrigerated chamber.

20. Refrigerating apparatus, including an outer heat-insulating casing provided with an inner gas-tight shell forming an interspace for circulation of carbon dioxide gas between it and the outer casing; a container for solid carbon dioxide in the upper portion of said chamber, arranged for overflow of gas therefrom into said interspace and provided with heavy heat insulation between it and the chamber to be refrigerated, thereby minimizing direct heat transfer; a metal condenser therein having its inlet at a relatively high level and its outlet at a lower level and having a transverse integral extension upon which solidified carbon dioxide refrigerant is supported, thereby affording an all metal path for transfer of heat from the condenser to the refrigerant and heat insulating material interposed laterally between the solid carbon dioxide and the condenser to minimize direct transfer of heat; a discharge conduit from the lower portion of the condenser ex-

tending into the refrigerated space, an evaporator in the refrigerated space into which said conduit discharges, a return conduit closing a closed circuit return for vapor from the 5 evaporator to the condenser, and means for controlling the rate of evaporation in the evaporator by and in accordance with the temperature of the refrigerated chamber.

21. Refrigerating apparatus, including an 10 insulating casing, a container for solid carbon dioxide provided with heavy heat insulation, thereby minimizing direct heat transfer to the exterior, a metal heat exchange device for circulation of a fluid to be cooled which includes a condenser portion and a transverse 15 metal plate extending therefrom and being within said container upon which the solidified carbon dioxide refrigerant is supported, thereby affording an all metal path for transfer 20 of heat from the heat exchange device to the refrigerant.

22. A method of refrigerating a plurality of compartments at different temperatures from a single refrigerant source which includes evaporating a liquid by heat absorbed 25 in the regions to be cooled, conducting the resulting vapor in operative relation to the refrigerant to recondense the same to liquid, said recondensation taking place in one portion 30 of a condenser while the heat is conducted to the refrigerant in a different portion of the condenser through a comparatively thick metallic path, conducting the liquid back to the regions to be cooled in separate 35 circuits, and controlling evaporation to control the temperatures in the refrigerated regions by controlling flow of fluid between the evaporators and the condenser.

23. A method of refrigeration which includes evaporating a liquid by heat absorbed 40 in a region to be cooled, conducting resulting vapor in operative relation to the refrigerant, to recondense the same to liquid, said recondensation taking place in one portion 45 of a condenser while the heat is conducted to the refrigerant in a different portion of the condenser through a comparatively thick metallic path, conducting the liquid back to the region to be cooled in continuous circuit, controlling evaporation to control the temperatures in the refrigerated region by preventing 50 return flow of the vapor to the condenser, and maintaining the rate of condensation substantially uniform by interposing suitable 55 insulation between said condensing portion and the refrigerant, thus preventing substantially all direct heat absorption therebetween.

24. An apparatus for refrigerating with solid carbon dioxide which comprises an outer 60 container, a solid carbon dioxide chamber within said container, a fluid condenser having a hollow portion for condensing the fluid and a fluid inlet and outlet communication with said hollow portion and a solid portion 65 extending therefrom, said solid portion being

arranged so that the solid carbon dioxide is in heat conducting relationship therewith whereby heat is absorbed mainly by conduction through said solid portion.

25. An apparatus for refrigerating with 70 solid carbon dioxide which comprises an outer container, a solid carbon dioxide chamber within said container, a fluid condenser having a hollow portion for condensing the fluid and a fluid inlet and outlet communication 75 with said hollow portion and a solid portion extending therefrom, said solid portion being arranged to support the solid carbon dioxide, whereby heat is absorbed mainly by conduction through said solid portion.

Signed at Chicago, in the county of Cook, and State of Illinois, this 23rd day of June, A. D. 1930.
